UNITED STATES PATENT OFFICE.

EDWIN C. LARRY, OF ROCHESTER, NEW YORK, ASSIGNOR TO GENERAL RAILWAY SIGNAL COMPANY, OF GATES, NEW YORK, A CORPORATION OF NEW YORK.

SWITCH THROW-ROD CONNECTION.

Application filed January 15, 1923. Serial No. 612,679.

To all whom it may concern:

Be it known that I, EDWIN C. LARRY, a citizen of the United States of America, residing at Rochester, in the county of Monroe and State of New York, have invented certain new and useful Improvements in Switch Throw-Rod Connections, of which the following is a specification.

This invention relates to switch throw-rod

connections for track switches for railways.

The principal objects and purposes of this invention contemplate the construction of a throw-rod connection of this class, which is readily adjustable to accommodate any difference in range or extent of movement of an operating lever or switch machine relatively to the required extent of movement of the switch points operated thereby, and to permit the necessary freedom of lateral movement to avoid sticking and binding of parts under any condition of use; in which the interengaging movable parts may be readily lubricated, which does not readily permit the ingress of dirt, moisture and the like, and which is provided with an opening to discharge the dirt or other foreign matter that may have worked its way into the mechanism.

Other objects, purposes and characteristic features of the invention will appear as the description thereof progresses.

In describing the invention in detail, reference will be made to the accompanying drawings forming part of this specification, and in which:

Figure 1 is a detail plan view of a short length of railway track and adjustable switch points coupled to the switch throw-rod by this improved connection;

Fig. 2 illustrates a plan view of the throw-rod connection shown in Fig. 1 on a slightly larger scale;

Fig. 3 is a side elevation of the device shown in Fig. 2, portions thereof being shown in cross section;

Fig. 4 is an enlarged fragmentary portion of Fig. 3; and

Fig. 5 is a perspective view of the cap member shown in Figs. 2 and 3.

Referring to Fig. 1, the reference numeral 1 indicates a through rail of a main or straight section of track, whereas the rail 2 is a through rail running into a turnout or siding. The switch points 3 and 4 as shown are rigidly connected by a lengthwise ad-

justable front rod 5, and by a suitable tie rod 6 to which is connected a throw-rod 7. This throw-rod 7 has its end threaded, as shown, and is connected to the tie rod 6 by the throw-rod connector of this invention, generally indicated by C. The throw-rod 6 is operated from a switch stand, switch and lock movement, or power switch machine.

This throw-rod connector comprises a main body portion or casing 10 of general cylindrical form which is formed with a laterally extending top flange 11, re-enforced by ribs 12, and provided with holes (see Fig. 2) to receive bolts 13 (see Fig. 1) by which the connector C is fastened to the tie rod 6. Around the ends of the casing 10 are external rounded ridges or beads 14. On the inside of the casing 10, near the middle, is a perforated partition or abutment 15, formed by an integral flange or by spaced lugs; and opposite this abutment 15 is a hole 16 in the casing 10 through which dirt, cinders, water or foreign matter may work its way out, this hole 16 constituting a drainage hole or port.

The threaded portion of the throw-rod 7 extends through the opening inside the flange forming the abutment 15, and has threaded thereon long cylindrical nuts 17 which are provided with integral hexagonal heads 18, and which are locked in place by lock nuts 19. These cylindrical nuts 17 are so spaced that the lost motion, due to end-wise movement of the throw-rod 7, will be equal to the difference of the throw of the switch machine or operating lever, and that of the tie rod in moving the switch points from one to the other extreme position. The cylindrical nuts 17 are somewhat smaller in diameter than the internal diameter of the casing 10 of the throw-rod connector, so that a certain amount of lateral movement will not cause binding of the parts and that the desired lost motion will be present and the proper throw be transmitted to the switch points. Near each end and at the top of the main body portion 10 is provided an oil hole 20 to facilitate the lubrication of the inter-engaging parts.

The cylindrical nuts 17 are of a length so that the cylindrical portion thereof extends outside the casing 10 at all times, and are provided with snugly fitting metal washers 21 which are just large enough to allow the nuts 17 to move freely endwise.

2
therein. These washers 21 are held against the flat ends of the casings 10 by suitable retaining members or caps 22, as more specifically shown in Fig. 5 of the drawings.

5 These caps 22 are preferably cast of malleable iron, and have integral therewith an extending lug 23 provided with a threaded hole for a set screw 24. Diagonally opposite to this lug 23 each cap 22 is provided 10 with two ears 25 spaced a short distance apart (about 45 degrees) to form in connection with the lug 23 a three-point attachment for the cap 22.

These ears 25 of each cap 22 are cast or 15 bent in a hook shape, as shown, to fit over the bead 14 of the casing 10. The spacing of these ears 25 and the length of the lug 23 is selected so that the cap 22 may be set over the end of the casing 10, the cap being first 20 tilted to engage the ears 25 and then straightened up. Since the caps 22 are made of malleable iron, the ears 25 and lugs 23 may be bent slightly to accommodate 25 slight variations in the outside diameter of the casings 10 and in the depth or width of the beads 14. After the cap 22 is in place, the set screw 24 is set up tight, its end being reduced and shouldered as shown to enter the oil passage 20 in the casing. 30 When the set screw 24 is tightened, the whole cap 22 is drawn up until the ears 25 grip the bead 14 tightly, whereupon the cap is held firmly in place and without any play.

The ears 25 and the lug 23 are so proportioned that when the cap is in place, there is an annular space for the washer 21 between the cap and the finished end face of the casing 10, as shown in Fig. 4. This space is a little wider or deeper than the thickness of the washer 21, at least enough to avoid binding or jamming of said washer; and the diameter of the space is considerably larger than the outside diameter of the washer 21, sufficient to allow said washer 35 to move with the nut 17 as the throw-rod 7 is rocked or tilted with respect to the casing 10. Each time the throw-bar 7 is shifted, the washers 21 are moved by the friction between them and the nuts 17 into 40 a relatively tight engagement with an end face of the casing 10 or an inside face of a cap 22, as the case may be, thereby providing a substantially dirt and water tight closure at each end of the casing 10 and 45 preventing the accumulation of dirt, snow, etc., inside of the casing to interfere with the necessary lost motion between said casing and the adjustable nuts 17 and destroy the adjustment. These washers 21, however, 50 are different from a packing, permit free turning and tilting of the throw-bar 7 as it is moved.

A throw-rod connector has thus been provided which allows endwise adjustment of 55 parts to take care of any change of the

relative position of the operating lever or switch machine with respect to that of the switch points to be operated, and which allows adjustment to vary the amount of lost motion so that the effective movement of the tie rod 6 may be such as desired all of which is accomplished by a simple and durable device which is reliable because it is constructed to keep out dirt and other foreign matter which would be apt to clog or bind 75 the relatively movable parts, which has a drainage opening whereby any foreign matter that may work its way into the casing 10 can pass cut through this opening. Further, this switch throw-rod connector is provided with oil holes which facilitate proper lubrication of the parts, and which are assured to be closed when not in use for lubrication purposes, because the cap members will not be properly clamped in place 80 unless the set screws extend into these oil holes.

Although one particular construction has been shown and described illustrating one physical embodiment of the invention, and the operation and principles thereof have been explained, nevertheless it should be understood that the form selected is merely illustrative, and does not exhaust all possible physical embodiments of the idea of 95 means underlying the present invention.

What is claimed and desired to be secured by Letters Patent of the United States, is:

1. A throw-rod connector comprising, an elongated casing having open ends and 100 provided with an internal abutment near its middle and having a drainage opening near said abutment and oil holes near its ends, a throw-rod extending through said casing provided with adjustable stops adapted to engage said abutment; and cap members closing the ends of said casing and said oil holes.

2. A throw-rod connector comprising, a 110 tubular casing having an internal abutment near its middle and provided with an oil hole near each end and a drainage hole near said abutment, a throw-rod extending through said casing, adjustable stops on said 115 throw-rod adapted to engage said abutment, cap members having hooks embracing the ends of said casing and provided with screws anchored in said oil holes.

3. A switch throw-rod connector comprising, a casing, a throw-rod entering the casing, an abutment in the casing through which the rod freely passes, two adjustable stop members on said rod, one on each side of the abutment having movement clearance 125 relatively thereto and normally resting on the bottoms of the casing chambers which contain them, said casing having a bottom dust, dirt and moisture clearance opening at the abutment, and annular cap members 130 clamped on the ends of said casing.

4. A switch throw-rod connector comprising, a casing, a screw threaded throw-rod entering the casing, an abutment in the casing through which the rod freely passes, 5 two nuts on the rod, one on each side of the abutment and having movement clearance relative thereto, close fitting washers on said nuts outside the ends of said casing, 10 said casing having a drainage opening through the bottom near the abutment, and detachable caps holding said washers in place.
5. A switch throw-rod connector comprising, a casing, a screw-threaded rod entering the casing, an abutment in the casing through which the rod freely passes, two cylindrical nuts on the rod each having a polygonal extension, one at each side of the abutment, close fitting washers on the cylindrical portions of said nuts arranged to bear against the end faces of said casing, 15 said casing having oil holes in the top near each end, and annular retaining members having screws normally closing said oil 20 holes and for holding said washers against said casing but allowing considerable transverse movement of said washers and nuts.
6. A switch throw-rod connector comprising, a casing having a bead at each end, a screw-threaded throw-rod entering the casing, an abutment in the casing through which the rod freely passes, two nuts on the rod one at each side of the abutment and having movement clearance relatively thereto and normally resting on the bottoms of 30 the casing chambers which contain them, and annular cap members encircling said nuts each provided with two hooks engaging said beads and provided with a set screw 35 directly opposite said hooks to form a three-point suspension closure, said casing having a bottom dust, dirt and moisture clearance opening at the abutment.
7. A switch throw-rod connector comprising, an elongated cylindrical casing provided with an internal abutment, a throw-rod extending through said casing, adjustable stop members on said rod arranged to engage said abutment and detachable caps 40 for closing the ends of said casing, each cap having three rigid projections adapted to fit over the ends of said casing and hold the caps in place.
8. A switch throw-rod connector comprising, an elongated cylindrical casing provided with an internal abutment, a throw- 45
- rod extending through said casing, adjustable stop members on said rod arranged to engage said abutment, detachable perforated caps encircling said rod and screw fastened to the ends of the casing in a manner to form annular grooves, and washers snugly fitting around said stop members and disposed in said grooves, said washers being of a diameter to allow considerable lateral movement of said stop members and throw-rod. 60
9. A switch throw-rod connector comprising, an elongated cylindrical casing provided with an internal abutment, a throw-rod extending through said casing, adjustable stop members on said rod arranged to engage said abutment, detachable perforated cap members surrounding said throw-rod and fastened to the ends of said casing 70 in a manner to form annular grooves defined by said cap members and the ends of said casing, and washers snugly fitting around said stop members and disposed in said groove, said washers being of a diameter to allow considerable lateral movement of said stop members and throw-rod, each of said cap members having three rigid projections to form a three-point suspension, one of said projections being provided with adjustable clamping means. 75
10. A switch throw-rod connector comprising, an elongated cylindrical casing provided with an internal abutment, a throw-rod extending through said casing, 80 adjustable stop members on said rod arranged to engage said abutment, detachable perforated cap members surrounding said throw-rod and fastened to the ends of said casing in a manner to form annular grooves 85 defined by said cap members and the ends of said casing, and washers fitting snugly around said stop members and disposed in said grooves which have an external diameter allowing considerable lateral movement of said stop members and throw-rod, said casing being provided with an oil hole near each end, each of said cap members having three rigid projections to form a three-point suspension one of which is provided with an 90 adjustable screw which normally extends into and closes its corresponding oil hole in said casing. 95
